DESIGN FOR A DISPENSER FOR SUGAR OR THE LIKE

Charles R. Bennett, Cleveland, Ohio

Application July 3, 1943, Serial No. 110,595

Term of patent 7 years

To all whom it may concern:

Be it known that I, Charles R. Bennett, a citizen of the United States and a resident of Cleveland, Cuyahoga County, Ohio, have invented a new, original, and ornamental Design for a Dispenser for Sugar or the Like, of which the following is a specification, reference being had to the accompanying drawing, forming a part thereof.

In the drawing:

I claim:

The ornamental design for a dispenser for sugar or the like, as shown.

CHARLES R. BENNETT.
